UNITED STATES PATENT OFFICE.

GOWEN H. CRAGG, OF BROOKLYN, NEW YORK.

DESIGN FOR A LADY'S COLLAR-BUTTON.

SPECIFICATION forming part of Design No. 13,610, dated February 13, 1863.

Application filed January 2, 1863. Term of patent 3½ years.

To all whom it may concern:

Be it known that I, GOWEN H. CRAGG, of Brooklyn, in the county of Kings and State of New York, have invented and produced a new and original Design for Ladies' Collar-Buttons, of which the following is a full, clear, and exact description.

Reference is to be had to the accompanying drawing, forming part of this specification, in which the figure is a perspective view of a lady's collar-button illustrating my design.

The leading feature of my design consists in a cross-bar upon the end of the button-post, having an ornamental knob at its center and a wire coiled around the neck of the knob and around the end parts of the cross-bar, and having leaf representations upon the ends of the coiled wires and upon the end parts of the cross-bar.

20 A is the post of a button, B. Upon the outer end of the post A is a cross-bar, C, which is engraved to represent a stem of a vine or branch. Upon the center of the bar C, and directly opposite the post A, is an ornamental knob, D. Around the neck of the knob D and the cross-bar C is coiled a wire, E, represent-

ing the leaf-stems of a plant. Upon the outer ends of the wires E, and upon the outer side of the end parts of the cross-bar C, are the representations of leaves, F, the forms of which 30 can be varied indefinitely without departing from my design.

I claim—

1. The design for a lady's collar-button herein shown and described, the same consisting 35 of the cross-bar C, having an ornamental knob, D, at its center, and a wire, E, coiled around the neck of the knob and the end parts of the bar.
2. The design for a lady's collar-button, the 40 same consisting of the cross-bar C, having an ornamental knob at its center, a wire, E, coiled around the neck of the knob and the end parts of the cross-bar, and the representation of leaves, F, upon the outer ends of the 45 wire E and the outer side of the end parts of the cross-bar C.

GOWEN H. CRAGG.
